UNITED STATES PATENT OFFICE.

HAROLD BINNEY, OF NEW YORK, N. Y., ASSIGNOR TO NEALON COMPANY,
A CORPORATION OF NEW YORK.

HOSE-SUPPORTER CLASP.

No. 836,081.

Specification of Letters Patent.

Patented Nov. 20, 1906.

Application filed January 3, 1905. Serial No. 239,379.

To all whom it may concern:

Be it known that I, HAROLD BINNEY, a citizen of the United States, and a resident of No. 10 Lexington avenue, in the borough of Manhattan, city, county, and State of New York, have invented certain new and useful Improvements in Hose - Supporter Clasps, of which the following is a specification.

10 This invention relates to garment - supporter clasps comprising a loop or like-acting member and a button, the shank of which is embraced in the loop, an edge portion of the garment, as the hem of a stocking or sock, being interposed therebetween and supported thereby.

Heretofore it has been customary to make the button-head of these clasps of circular contour and to provide it with an axially-disposed shank, or at least to have a substantial portion of the button-head depend below the shank, so that in use the button-head covers the lower transverse or connecting portion of the loop.

25 In practice there is a tendency of the stocking or other supported garment to slip from its engagement. My present improvement consists in providing a button-head of non-circular shape, ordinarily in the form of a polygon with rounded corners, with which the stocking-hem engages.

30 I preferably provide laterally and upwardly extending wings and find increased advantage in attaching this polygonal button-head to its supporting-back by a shank at or adjacent to its lower edge or corner.

35 In the accompanying drawings, Figures 1 and 2 are respectively a front elevation and a vertical section of a clasp embodying my invention. Figs. 3 and 4, as well as Figs. 5 and 6, are views corresponding to Figs. 1 and 2 of modified forms of the device.

40 Referring to Figs. 1 and 2 of the drawings, 1 designates a loop, usually made of metal, either in sheet or wire form. As shown, it has the usual pear-shaped or "nail-head" slot 11, the lower part 12 of which is of reduced width. The lower side bars 13 of the loop 1 are shown as approximately parallel 45 and as connected by a curved transverse portion 14. Behind the loop 1 is supported a back 2, to which is attached, by means of a shank 22, a button-head 21. The button-head 21 is of triangular shape, having up-

wardly and outwardly extending wings or 55 corner portions 23. The shank 22 is secured to the rear face of the button-head 21 substantially below its center and, as shown, approximately at its lower corner. In this way any tendency of the downward strain 60 on the stocking to raise the button from its normal lowermost position in the loop 12 is eliminated, while all the diagonally and directly downward strains caused by the engagement of the corners 23 with the fabric 65 act to hold the button firmly in such lowermost position. It is also evident that the corners 23, while not so sharp as to bite into or tear the fabric, effectually prevent its slipping.

70 In Figs 3 and 4 the button-head 21, is shown as of quadrilateral shape with rounded corners and extending, as before, only upwardly and laterally from the shank 22. It is clear that in this form, as in that just 75 described, all the strains will coöperate to maintain the button in its place and to prevent the disengagement therefrom of the stocking or like article.

75 The button-head 212 (shown in Figs. 5 and 80 6) is approximately triangular in form with upwardly and outwardly extending wings 23, as in Figs. 1 and 2; but in this case the shank 22 is attached to the lower face of the button-head at approximately its central point. In 85 this form of the device there will exist the tendency above described of the stocking or sock to raise the button-head from its seat; but this will be resisted by the downward strains at the wings 23; but even if an up- 90 ward movement of the button should occur the engagement of the corners 23 with the fabric will be sufficient to prevent the disengagement of the stocking, which might easily occur with a button-head of circular form 95

I have filed two applications of even date herewith, which have received Serial Nos. 239,377 and 239,378, respectively. In the first of these is shown and claimed the transverse corrugations of the back 2, described 100 herein, and in the second the button-head is shown and claimed as provided with an eccentrically-disposed shank secured to its rear face. It is obvious that I do not herein claim anything claimed in either of those applications.

105 By the term "polygonal button-head," as used in the claims, I include any button-head

having ears and the contour of which departs substantially from the ordinary circular form.

I have illustrated the button-head, its shank, and its supporting-back as integral and as they would appear if molded from a rubber compound; but it is evident that the material or construction of the device, except as described, forms no part of my present invention and that modifications other than those shown may be employed without departing from its spirit.

Having thus described my invention, what I claim, and desire to secure by Letters Patent, is—

- 15 1. A garment-supporter clasp comprising a loop having a slot narrowed at its lower end and a button having a polygonal head and a shank of less width than the lower portion of said slot and adapted to pass freely thereinto.
- 20 2. A garment-supporter clasp comprising a loop having a slot narrowed at its lower end and a button provided with a head having upwardly and laterally directed angular corners, and a shank for engaging in said loop.
- 25 3. A garment-supporter clasp comprising a loop, and a button having a head of approxi-

mately angular form having upwardly and laterally extending corners and a shank for engaging in said loop.

4. A garment-supporter clasp comprising 30 a loop, a button-supporting portion, and a button having a polygonal head secured to said supporting portion substantially below the center of said button-head for engaging in said loop.

5. A garment-supporter clasp comprising a loop and a button having a polygonal head, and a shank located approximately at the lower edge of said head for engaging in said loop.

40 6. A garment-supporter clasp comprising a loop and a button having a head of approximately triangular form with a lower corner and a shank located at the lower corner of said head for engaging in said loop.

In testimony whereof I have signed this specification in the presence of two subscribing witnesses.

HAROLD BINNEY.
